[57] CLAIM

An ornamental design for a poster hanger, as shown and described.

DESCRIPTION

FIG. 1 is a reduced perspective view of a poster hanger showing my new design;

FIG. 2 is an enlarged rear elevational view thereof, with the center broken away for convenience of illustration;

FIG. 3 is a left side elevational view with the opposite side being a mirror image thereof;

FIG. 4 is a bottom plan view thereof, with the center broken away for convenience of illustration.
